UNITED STATES PATENT OFFICE.

GEORGE H. NEIDLINGER, OF EAST ORANGE, NEW JERSEY.

CLOSING-GUIDE FOR COLLAPSIBLE TUBES.

1,383,141.

Specification of Letters Patent. Patented June 28, 1921.

Application filed January 14, 1920. Serial No. 351,295.

To all whom it may concern:

Be it known that I, GEORGE H. NEIDLINGER, a citizen of the United States, and a resident of East Orange, in the county of 5 Essex and State of New Jersey, have invented a new and Improved Closing-Guide for Collapsible Tubes, of which the following is a full, clear, and exact description.

This invention relates to collapsible tubes 10 and the manufacture of collapsible tubes. More particularly, the invention relates to means and methods for properly closing the end of the tube.

A collapsible tube, as is well known, is a 15 container used for the distribution and sale of all manner of toilet articles, such as shaving creams and the like preparations. The collapsible tube is capable of being rolled from one end to eject the contents from the 20 other end. The tube as used in the market usually bears the name of the contents with directions for administering same, and with the manufacturer's name printed on the tube for observance by purchasers and users.

25 In manufacturing collapsible tubes it is the usual practice to employ a sheet-metal blank which is placed in a special machine with punching dies which bend up the metal blank to form a cylindrical tube. The tube is then 30 printed to show the directions, contents, the name of the manufacturer, and other pertinent information. One end of the cylinder is usually closed with a screw-threaded cap, and the other end is closed by pinching the 35 collapsible tube together after being filled, after which the pinched end is folded over to form a hermetically-sealed joint. It is the pinching and folding operation of the open end to form a sealed joint with which 40 my invention has to do and which particularly forms the basis of the present disclosure.

In the filling of collapsible tubes on the 45 quantity production basis, the operators employed to close the open cylindrical ends of the collapsible tube do not have sufficient time to pains-takingly apply the closing machine to execute the pinching operation so as to make the sealed end come in line with or 50 fall within the same plane as the printed panels on the tube. The inaccuracy of the application of the closing machine to the tube causes the printed directions, with the name of the contents and the manufacturer's 55 title, to be twisted, offset or deformed from the desired position, and the completed tube

with its sealed-end printed portions do not form a symmetrical and well-shaped container. When the closed and sealed end of the tube does not come within the same 60 plane as the printing on the tube, the container, when sitting on a shelf or displayed in a drug-store cabinet, will not have its printed portions facing directly the observer, but the printed directions, the name 65 of the contents and the manufacturer's title, will be partly obscured by extending around the cylindrical body of the tube and not directed in the plane of vision.

It is fitting, therefore, that the primary 70 purpose and object of my invention is to provide means and manufacturing methods to facilitate the closing and sealing operation of the collapsible tube to the end that the operators and mechanics employed in a 75 collapsible-tube filling factory will be guided and directed in applying the closing machine to the tube so that the finally closed end will be in the same plane with the printed portions, or will be alined with the 80 printed portions of the collapsible tube in order that the tube will better display the printing when supported in a vertical position, and will form a better made product and present a more shapely and symmetrical 85 appearance than has heretofore been possible.

To this end I present the following invention, and display in picture form ways and 90 means of effectually carrying out the afore- said processes. A collapsible tube and closing machine constructed and used in accordance with the plans of my invention employs a guide line printed on the bottom portion 95 of the tube to indicate the position where the closing machine must be applied in order to form a well-closed end even with and in the same plane with the printed portions of the tube. The crux of my invention, therefore, relates to means to indicate the relative position of the closing machine with the printing on the collapsible tube in order 100 that the closing machine may be applied parallel to the bottom end of the tube; and, furthermore, to cause the folded end to assume 105 a folded position perpendicular to the axis of the tube.

In the following description there is set forth a more detailed analysis of my invention, and in the appended claims there are defined several modifications and forms of the 110 invention. The accompanying drawings dis-

close one example of a collapsible tube having guide means for visibly displaying the proper place to apply the pinching tool or closing machine.

5 Figure 1 illustrates a tube which has been sealed, and flattened out with a view of more clearly illustrating the application of my invention.

10 Fig. 2 is a perspective view of a tube employing my improved construction, and prior to its application to a crimping machine, and

15 Fig. 3 is a fragmentary perspective view of the upper end of the tube subsequent to its having been completed, and subjected to the conventional crimping action.

20 Referring now more particularly to Fig. 1, it will be seen that the illustration of this figure has been resorted to with a view of clearly indicating the position of the usual trade-marks, advertising matter and descriptions upon the body of the tube, *i. e.* preferably at diametrically opposite points in the face of the finished tube.

25 With a view of avoiding a confusion I have indicated this advertising matter, directions, etc. by means of panels 7 and 8 appearing upon the body 6 of the tube, it being understood that the body of the same presents in normal appearance, the shape shown in Fig. 2, in which this body is identified by the reference numeral 9.

30 As has been pointed out in the preamble, considerable difficulty has been experienced 35 incident to the fact that the crimping machine applied to the open end of the filled tube does not engage the same in planes parallel to the advertising. Thus the advertising and directions are not freely presented 40 to a customer, aside from the fact that in use, and upon the closed end of the tube being pinched and rolled to effect a discharge of the contents, that the reading matter is often destroyed to a point at which the same 45 may not be read.

45 With this in view, I conveniently provide an indicating mark of any suitable character, which might conveniently be termed a closing guide. This mark is identified by 50 the reference numeral 10, and it will be seen, reference being had to Figs. 1 and 2, that the same is substantially in line with one of the panels. Thus an indicating means is provided for the operator of the crimping or 55 clamping machine, and upon the operator

presenting the filled tube to the jaws of the same, in a position at which the jaws will even substantially align with the indicating mark 10, it will be appreciated that the free edges of the tube will be closed in the manner indicated in Fig. 3, *i. e.* that the advertising matter and directions will appear at diametrically opposite points in the face of the tube 9, and not in line with the line of bending, to which the body of the tube will be subjected while in use.

60 From the foregoing it will be appreciated that I have provided means acting as a closing guide which will serve to permit the operator of a clamping or crimping machine 65 to properly associate the tube with the same, to insure a proper closing of the free end of the tube whereby the panels 7 and 8 will be freely presented to the view of the customer, and may subsequently be examined 70 even upon the tube having its contents discharged.

75 Obviously any form of indicating mark best adapted to immediate recognition on the part of the operator might be utilized 80 without in the slightest departing from the scope of my claims, which are;

Having thus described my invention, what I desire to secure by Letters Patent is:

1. As an article of manufacture, a collapsible tube having panels of written matter appearing upon its face, and means also appearing upon the outer face of said tube, and being substantially in line with one of said panels for indicating the point at which 90 the jaws of a crimping machine should contact for properly closing the open end of said tube subsequent to the same being filled.

2. As an article of manufacture, a collapsible tube having panels of written matter upon its face, and means also appearing upon the outer face of said tube and adjacent its lower edge, and being substantially in line with one of said panels for indicating the point at which the jaws of a crimping machine should contact for properly closing the open end of said tube subsequent to the same being filled.

3. As an article of manufacture, a collapsible tube having panels of written matter appearing upon its outer face, said tube being formed with a closing guide also visible upon the exterior face of said tube and adjacent its free edge.
